UNITED STATES PATENT OFFICE.

WILLIAM A. SCHLEICHER AND MILFORD LEWIS, OF CLEVELAND, OHIO, AND
HENRY C. SWAN, OF OSHKOSH, WISCONSIN.

DESIGN FOR A HARNESS-LOOP.

SPECIFICATION forming part of Design No. 28,982, dated July 5, 1898.

Application filed June 6, 1898. Serial No. 682,772. Term of patent 14 years.

To all whom it may concern:

Be it known that we, WILLIAM A. SCHLEICHER and MILFORD LEWIS, of Cleveland, in the county of Cuyahoga and State of Ohio, and HENRY C. SWAN, of Oshkosh, in the county of Winnebago and State of Wisconsin, have invented a new and original Design for a Harness-Loop, of which the following is a full, clear, and exact description, reference being 10 had to the accompanying drawings, forming part of this specification, in which—

Figure 1 is a perspective view of our improved loop, and Fig. 2 is a transverse section of the same.

15 The design relates to harness-loops; and it consists in a loop having a base portion of general rectangular shape and provided with arms carrying the rear bar, this rear bar having upper projections which form between 20 them a recess for the heel of a buckle-tongue.

In the drawings, 2 represents the base of a buckle-tongue which is of general rectangular shape, the ends being slightly curved, as clearly shown in Fig. 2. Extending from the ends of the base are the arms 3, which carry 25 the rear bar 4. This bar is straight on its under side, while on its upper side are provided projections or lugs 5, which form between them the recess 6.

We claim—

30 The design for a harness-loop, substantially as herein shown and described.

In testimony whereof we have hereunto set our hands.

WILLIAM A. SCHLEICHER.
MILFORD LEWIS.
HENRY C. SWAN.
